(57) **CLAIM**

The ornamental design for an excavator cab, as shown and described.

DESCRIPTION

The patent or application file contains at least one drawing executed in color. Copies of this patent or patent application publication with color drawing(s) will be provided by the Office upon request and payment of the necessary fee.

Reproduction 1.1 is a top right rear perspective view of an excavator cab.

Reproduction 1.2 is a top left front perspective view of an excavator cab.

Reproduction 1.3 is a rear view of an excavator cab.

Reproduction 1.4 is a top front right perspective view of an excavator cab shown in use condition mounted to an excavator which forms no part of the claimed design.

Reproduction 1.5 is a front view of an excavator cab.

Reproduction 1.6 is a right side view of an excavator cab. The lightly shaded gray and color areas shown in reproduction 1.4 form no part of the claimed design.
